BOILER AND SUPERHEATER

Eugene L. Schellens, Ridgewood, N. J., and Christopher A. Schellens, Marblehead, Mass., assignors to C-S Engineering Company, Englewood, N. J., a corporation of Delaware

Application March 17, 1939, Serial No. 262,440

6 Claims. (Cl. 122—463)

This invention relates to boilers, especially locomotive boilers and to superheaters, especially of the type wherein a portion of the length of the usual fire tubes or flues extends through a compartment in the water space of the boiler but from which the water is excluded and through which steam is circulated to be superheated by the heat of the flues.

Objects of the present invention include a boiler and superheater of the type set forth wherein the superheater compartment is supported mainly by the boiler shell; wherein the flues within the compartment are protected in an improved manner from the radiant heat of the fire; wherein the steam flows in a progressive and efficient manner in contact with the superheating flues; wherein the pressure difference between the interior and exterior of the compartment is small and practically independent of the operation of the locomotive; and wherein provision is made for improved means for leading steam to and from the compartment.

A further object of the invention is generally to improve the construction of boilers and superheaters of the type set forth.

Fig. 1 is a longitudinal sectional elevation through the rear part of a locomotive boiler embodying the present invention.

Fig. 1a is a continuation of the section of Fig. 1 showing the front part of the locomotive boiler.

Fig. 2 is a transverse section through the boiler and superheater, taken along line 2—2 of Fig. 1.

Fig. 3 is a partial longitudinal section through a locomotive boiler illustrating a different form of superheater.

Fig. 4 is an enlarged transverse section of the superheater and boiler shell taken along line 4—4 of Fig. 3.

Fig. 5 is a sectional detail taken along line 5—5 of Fig. 4.

Fig. 5a is a sectional detail taken along line 5a—5a of Fig. 4 and illustrating particularly the manner of securing a vertical partition plate to the superheater shell.

Fig. 6 is a longitudinal sectional elevation, partly broken away, of a locomotive boiler showing a further modified form of superheater.

Fig. 7 is a transverse sectional elevation of the locomotive boiler and superheater, taken along line 7—7 of Fig. 6.

Fig. 8 is a sectional detail of a saturated steam passage taken along line 8—8 of Fig. 7.

Fig. 9 is a partial longitudinal section through a locomotive boiler illustrating a further modified form of the invention.

Fig. 10 is a transverse section taken along line 10—10 of Fig. 9.

Fig. 11 is a sectional detail taken along line 11—11 of Fig. 10.

Fig. 12 is an enlarged sectional detail taken along line 12—12 of Fig. 10.

In the construction illustrated in Figs. 1, 1a, and 2, as applied to a locomotive boiler to which the invention is more particularly intended, the boiler comprises the boiler shell 10, the rear tube sheet 12, which is set back or rearwardly of the throat 14, the fire box 16 with its siphons or water legs 18 located in the rear of the rear tube sheet, the front tube sheet 20, the smoke box 22 with its steam draft nozzle 24, stack 26, and a plurality of straight fire tubes 28 extended between and fixed in the front and rear tube sheets.

The boiler shell 10 is surmounted by a smaller diameter shell 30 which is approximately co-extensive with the length of the boiler shell. The two shells are open at their confronting parts and are secured together by being welded or otherwise fixed to an interposed tie plate 32 which extends across the openings of both shells and connects them together in the manner and for the purpose disclosed and claimed in our co-pending application Serial No. 51,616, filed November 26, 1935.

Said tie plate is formed with a plurality of steam passages 34 therethrough so that the steam can pass from the upper part of the boiler shell 10 into the upper shell 30 which constitutes the major steam space of the boiler. With this arrangement the shell 30 can have an exceptionally high water level therein and have a large number of fire tubes. This construction is particularly advantageous with high speed locomotives where the tendency is to increase the diameter of the drivers to a point where the possible boiler shell diameter is reduced to a dimension where the gas area through the fire tubes is not sufficient for the requisite boiler power. With the described construction substantially the whole front tube sheet is available for tubes, whereas, in conventional practice about one-third of the upper portion is reserved for steam space. By the use of the upper shell 30 the volume of steam space is greatly raised and the number of tubes is greatly increased by carrying the upper shell to the clearance limit and utilizing substantially the full tube sheet area for tubes and carrying the water level above the top of the tube bank and close to the top of the boiler shell. As stated above the rear tube sheet 16 is back of the throat 14. The rear

55 tube sheet 12 is back of the throat 14. The rear

tube sheet is provided with a lower drop portion 36 confronting and spaced from a similar drop portion 38 of the boiler shell to form a water leg into which the lower ends of the siphons open. The fire tubes 28 are pitched or sloped downwardly from the front to the back. The rear tube sheet and furnace crown sheet 40 is located close under the top of the boiler shell, and under the water level, the fire box wrapper sheet 42 being carried upwardly to about the top clearance line or close to the line of the top of the steam shell 30. This arrangement utilizes the increased tube space and water level in increasing the steaming capacity of the boiler. The steam space under the wrapper sheet and above the water level over the crown sheet communicates with the steam shell 30 through a passage 44 in the end of the steam shell.

The superheater 45 in accordance with this invention is located within the boiler shell 10 close to the rear tube sheet 12 and remote from the front tube sheet 20 and encloses a large number of fire tubes 28. The superheater includes front and rear superheater tube sheets 46 and 48, respectively, suitably spaced apart lengthwise of the tubes to provide a sufficient extent of tube length within the superheater for the purpose of superheating the steam. The tube sheets 46 and 48 are perforated in conformity with the tube layout and the fire tubes pass through these sheets and are rolled or otherwise arranged in steam tight engagement therewith. As will be explained more fully hereinafter there is but small pressure difference within and without the superheater so that the steam pressure tending to cause leakage of steam between the tubes and superheater tube sheets is small.

The superheater tube sheets extend transversely of the boiler shell into edgewise contact with the inner face of the boiler shell and are welded in a steam tight manner thereto. The locomotive shell 10 thus also constitutes a part of the superheater shell. The superheater tube sheets are terminated preferably in a straight line above the tube collection but under the water level and are welded to a top sheet 50 which also is welded to the boiler shell and forms a top closure for the superheater. The bottom edges of the superheater tube sheets are also terminated preferably in straight lines transversely of the bottom of the boiler shell and are welded to a bottom sheet 52 which sheet is also welded to the boiler shell and constitutes the bottom closure of the superheater.

The space 54 under the bottom closure plate 52 and above the bottom of the boiler shell contains fire tubes 28 and constitutes a water passage connecting the water spaces 55, 57 on opposite sides of the superheater by which a directed circulation of water lengthwise of the boiler is effected.

The interior of the superheater shell is divided into left and right hand transverse compartments 56, 58, see Fig. 2, by a vertical partition sheet or plate 60, the upper and lower horizontal edges of which are welded to the upper and lower closure plates 50, 52, the vertical edges preferably being free from attachment to the front and rear sheets although close thereto so as to permit free expansion of the fire tubes. While steam can leak around the unattached edge of the partition sheet the leakage will be small since the pressure difference in the two compartments 56, 58 is low. The plate 60 can, however, be welded to the tube sheets where, as here illustrated, tubes near the

plate have been omitted so that expansion of the other tubes is not hindered by the welded plate 60.

The superheated steam issues from the top of the right hand compartment 58 through a vertical pipe 62 fixed to the top shell plate 50 and passing through the tie plate 32 and communicating with a superheated steam pipe 64 which is located centrally within the steam shell 30 and extends forwardly through the front end of the shell where it opens into a superheated steam throttle valve 66 from which the steam can flow in any suitable manner not herein shown to the locomotive cylinders.

Saturated steam from the steam shell 30 enters the top part of the left hand superheater compartment 56 by means of a tube 68 opening through the rear part of the superheater top plate 50 and through the left hand side of the aforesaid tie plate 32 where it communicates with a chamber 70 formed by end plates 72 and 74 and an arcuate side plate 76 which partially surrounds but is spaced from the superheated steam pipe 64 and has its bottom edge welded to the tie plate 32 along the middle line thereof. The upper edge of the plate 76 is spaced below the top of the steam shell 30 and provides a long entrance slot or opening 78 through which saturated steam in the steam shell can enter the compartment 70 and pass into the superheater. The steam openings 34 through the tie plate confronting the plate 76 are located in the right hand side of the plate when viewed from Fig. 2 so that the steam in the boiler shell is constrained to pass into the steam shell and thence into the compartment 72 through the slot 78. This arrangement tends to separate water out of the saturated steam before passing into the superheater and an inclined baffle plate 80 is located in front of the slot 78 for the same purpose.

The compartment 56 of the superheater is formed into a plurality of superposed steam flow passages by the vertically spaced horizontal partition plates 82, 84, 86 and 88 which plates are welded to the boiler shell and to the vertical partition plate 60. The plates 82, 86 are terminated close to the rear tube sheet 48 to form a closure therewith but preferably are not rigid therewith and are spaced from the front tube sheet 46 to provide steam passages therebetween. The plates 84, 88 on the other hand at their ends are terminated close to the front sheet 46 and are spaced from the rear sheet 48 for the same purpose. This arrangement causes the incoming steam to flow horizontally lengthwise of the fire tubes and alternately with and against the directions of the flow of the combustion gases in the tubes and progressively downward. The superheater compartment 58 is divided into similar flow passages by partition plates 90, 92, 94 and 96 arranged similarly to the aforesaid partition plates except that the plates 90, 94 are spaced from the rear tube sheet 48 and the plates 92, 96 are spaced from the front tube sheet 46. The vertical partition plate 60 is provided with a series of openings 98 located throughout the longitudinal length of the sheet so that the steam can flow transversely of the boiler shell and the fire tubes from the lowermost part of the compartment 56 under the plate 88 to the lowermost part of the compartment 58 under the partition plate 96. In its flow in intimate heating contact with the fire tubes the initially saturated steam becomes highly superheated to a temperature

closely approximating the temperature of the fire tubes within the superheater.

In the modification illustrated in Figs. 3, 4, 5, and 5a, the locomotive boiler is provided with a cylindrical boiler shell 10a and the usual front and rear tube sheets of which the rear tube sheet 12a is illustrated in Fig. 3 and straight fire tubes 28a extended between the tube sheets.

In this modification the superheater 100 is located within the boiler shell in close proximity to the rear tube sheet and includes a wrapper sheet or shell 102 which encloses all of the fire tubes and is approximately elliptical in cross-section to conform with a configuration of the rear tube sheet and the tube group thereat. The superheater is provided with front and rear superheater tube sheets 104, 106 which are welded to the shell sheet 102 and through which tube sheets the fire tubes pass as heretofore described, the tubes being secured in a pressure tight manner in the superheater tube sheets.

The superheater is formed with right and left hand compartments 108, 110 by a pair of vertical plates 112, 114 spaced transversely of the boiler shell to provide a vertical passage 116 therebetween terminated above the bottom of the superheater shell and also under the top of said shell where they are connected with end plates 118, 120 that are also connected with the wrapper shell 102 to form a steam entrance compartment 122 into which saturated steam can flow from a pipe 124 taking steam from the steam dome 126. Thus saturated steam can flow downwardly between the plates 112, 114 and spread in opposite directions into the lower part of the compartments 108, 110. Upwardly inclined vertically spaced partition plates 128 are located in said compartments and are welded to the vertical plates 112 or 114 and the superheater shell 102. Alternate plates are also terminated close to one superheater tube sheet and spaced from the other so as to provide a sinuous passage for steam alternately back and forth horizontally in the line of the fire tubes and progressively upward from the bottom of the compartment to the top thereof where the steam passes outwardly through separate superheated steam pipes 130, 132 and thence in any desired manner to the throttle and locomotive cylinders. The partition plates 128 also act as stay members for the elliptical superheater shell. The plates 112, 114 are tied together at longitudinally spaced intervals by intervening plates 134 as illustrated in Fig. 5. The lower edges of said plates 112, 114 are terminated upon ribs 115 fixed to and upstanding from the lower part of the superheater shell and have depending projections 117 located close beside and welded to said ribs to ensure a strong connection between the superheater shell and said plates.

In the modification illustrated in Figs. 6, 7 and 8, the superheater 136 is enclosed within the cylindrical boiler shell 138 of the locomotive around certain but not the lowermost ones of the first tubes 140 and disposed between the front and rear tube sheets 142, 144 and relatively close to the rear tube sheet 144. In this modification, the superheater comprises the front and rear superheater tube sheets 146, 148 through which the fire tubes pass. Said sheets have circularly formed ends which confront and are spaced from the interior of the boiler shell and are joined by cylindrically formed shell sheets 150 which are spaced from the boiler shell to provide saturated steam passages 152, 154 therebe-

tween. Said passages are closed at the ends by plates having arcuate sections 156 interposed between the superheater shell 150 and the boiler shell 158 and welded to both. The bottoms of the passages are closed by plates 164.

The superheater is closed at the top by an upwardly arched plate 158 which overlies the tops of the passages 152, 154 and is welded to the superheater tube sheets and also to the shell sheets 150 and the boiler shell. An opening is formed in the arched plate 158 at the rear part and at each side part thereof registering with the passages 152, 154 and steam entrance boxes 160, 162 are formed over the openings. The cylindrical superheater shell sheets are reinforced by arcuate ribs 166 located in said passages 152, 154. The arched top closure plate is reinforced by longitudinal ribs 172. The superheater is closed at the bottom by a horizontal closure plate 168.

Saturated steam is taken from the boiler steam dome 174 through a moisture separator 176 from which branch pipes 178 and 180 conduct the steam to the separate steam boxes 160, 162. The saturated steam thence flows through the passages 152, 154 and enters the interior of the superheater through longitudinal slots 182 in the bottom part of the shell sections 150. A plurality of vertically spaced horizontal partition plates 184 are extended between the tubes and welded to the superheater shells. Certain plates have passages 186 through the middle part thereof, and other alternate plates have passages 188 through side parts thereof. The arrangement is such that the steam in the lower part of the superheater flows inwardly from the sides to the opening 186 in the lowermost partition plate, being guided upwardly by the interposed baffle plate 190 and thence in opposite directions transversely of the fire tubes and through the side openings in the next upper partition plate and so on to the upper part of the superheater where the steam enters the upper compartment 192 under the top plate 158. Superheated steam is taken from said compartment by pipes 194, 196 opening through the top plate at the sides and forward part thereof and passes in any suitable manner through a superheated steam throttle valve 198, and thence to the locomotive cylinders.

The superheater arrangement illustrated in Figs. 9 through 12, is a modification of that illustrated in Figs. 6, 7 and 8, the superheater of Figs. 9 through 12 being suspended from instead of being welded, in part, to the boiler shell. In these figures the superheater 200 comprises a drum having cylindrically shaped outer side sheets 202, and 204 and top and bottom closure sheets 206, 208 of inverted cylindrical shape. Front and rear superheater tube sheets 210, 212 are welded to the side and the top and bottom sheets to form a pressure tight drum and the fire tubes 214 are extended through the tube sheets as heretofore. The tube sheets have straight top edges 216 so that they upstand above the top sheet 206 and form convenient attaching means for hangers 218 which at their lower ends are fixed to the upwardly projecting parts of the tube sheets and at their upper parts are attached to brackets 220 fixed to the interior of the boiler shell 222. The superheater drum thus is suspended from the boiler shell and is spaced from the inner face thereof.

The drum is provided with cylindrical inner side sheets 224, 226 which confront and are

spaced inwardly from the outer cylindrical sheets 202, 204 to provide saturated steam passages 288, 230 therebetween leading from the top to the bottom part of the drum sides. The inner side sheets have outwardly extended flanges 232, see especially Fig. 12, closely confronting but spaced from the tube sheets and welded at their edges to the outer sheet. The passages are closed at the top and bottom by the top and bottom sheets 206, 208.

Said inner sheets, at the bottom part thereof, are provided with a series of vertically elongated and preferably vertically staggered slots 209 therethrough through which saturated steam can flow from said passages into the interior of the drum and into contact with the fire tubes therein.

Saturated steam is admitted into the upper parts of said passages 228, 230 through elbows 234, 236, which are located partly within the drum and have their outlet parts welded in the upper part of the inner side sheets and their outlet parts extended through and welded in the top sheet 206. Said elbows receive saturated steam through pipes 238, 240 connected to a separator 242 located in and receiving saturated steam from the steam dome 244 of the boiler shell.

A series of horizontally-disposed vertically spaced partition plates 246, 248, 250, 252, 254 are located within the superheater drum as in Fig. 7, the plates 246, 250, 254 having apertures 256 in the middle parts thereof and the alternate plates 248, 252 having apertures 258 in the end parts at the inner side sheets 224, 226. Thus steam is constrained to flow alternately inwardly and outwardly and progressively upward crosswise of the fire tubes and become superheated. Said partition plates are preferably welded to the inner side sheets and thus constitute tie members therebetween but are close to although not fixed rigidly to the tube sheets, as has been explained heretofore.

A baffle sheet 260 is located above the tubes in above the uppermost partition sheet 254 and is inclined downwardly in both directions from the high middle part thereof to guide the superheated steam to flow rapidly over the fire tubes immediately thereunder to outlets 264, 266 opening through the front superheater tube sheet into the upper compartment of the superheater drum above the top plate 254 and at the side parts of the drum. The superheated steam from the outlets passes into a single pipe 268 and thence through the throttle 270 to the locomotive cylinders.

In all of these modifications it is to be noted that the superheater shell surrounds the straight fire tubes and receives heat from the tubes. The superheater is close to the rear tube sheet so that the combustion gases are highly heated when they are within the superheater part of the fire tubes, yet there is a sufficient length of water space between the superheater and the rear tube sheet to reduce the intense heat of the combustion gases of the fire tube to a lower value that will not damage the superheater. The superheater thus is protected against burning out since it is not exposed to the radiant heat of the fire box.

Preferably the length of water evaporating surface of the fire tubes intervening between the rear tube sheet and the superheater is made as small as is consistent with adequate protection

of the superheating surfaces against radiation from the fuel bed.

The flow of heat through the heating surface of the boiler as a whole is to a large extent counterflow. Thus the superheater which handles the hottest steam is subjected to the hottest flue gases and the evaporative surface in front of the superheater which evaporates steam at a lower mean temperature is subjected to the somewhat cooled gases. There is no surface in the boiler in which the temperature difference is low, and wasted heating surface is therefore avoided.

The superheater at all times is filled with steam under substantially the saturated steam pressure except for the slight pressure drop there may be that is caused by the flow of steam through the superheater. Thus, the pressure on the superheater shell is small and the shell can be made of light construction.

20 Extreme care need not be made in providing joints in the superheater that are tight against high pressure because the pressure difference between the inside and the outside of the superheater is small. Furthermore, leaks are of minor 25 importance since the steam cannot mingle with the combustion gases to cause corrosion of the parts in contact therewith.

All superheater headers and special superheater tubes and flues are eliminated.

30 The superheater element of the fire tubes is in series with two evaporating elements. This makes for a larger gas area since with any section of the tubes, only two fluids are involved. This feature is important as the available gas area which is limited by the boiler shell diameter limits the size of the locomotive.

We claim:

1. In a locomotive boiler, superimposed communicating large and small boiler shells, the large 40 boiler shell adapted to contain water to be evaporated into steam and the small boiler shell constituting a steam space for the large shell, fire tubes in said large shell, a superheater in said large shell surrounding a part of the length of 45 said fire tubes and providing water evaporating spaces on opposite sides thereof, a saturated steam pipe connecting said steam shell with said superheater, and a superheated steam pipe communicating with said superheater and extended 50 in and lengthwise of said steam shell.

2. In a locomotive boiler, a boiler shell, fire tubes in said shell, a superheater shell within said boiler shell surrounding a part of the length 55 of said fire tubes, means providing steam passages between said boiler shell and superheater shell to the tube collection communicating with the lower part of said superheater shell, partition plates within said superheater shell extended crosswise thereof providing steam flow transversely of said fire tubes and upwardly therebetween to the upper part of said superheater shell, and means for conducting superheated steam 60 away from said superheater shell.

3. A locomotive boiler comprising a boiler shell, 65 a smaller steam shell on and approximately co-extensive with the length of said boiler shell and having communication therewith, a furnace shell having a rear tube sheet located rearwardly of said boiler shell, a front tube sheet, fire tubes 70 extended between said tube sheets, said furnace shell including a crown sheet close to the projected top line of the boiler shell, and a wrapper sheet about the furnace shell above the crown sheet and above the top line of the boiler shell,

and means providing endwise communication between the steam space over said crown sheet and said steam shell.

4. In a boiler, a boiler shell, fire tubes therein, a superheater drum within said shell surrounding said fire tubes, said drum including outer and inner spaced sheets confronting the boiler shell providing steam passages opening into the tube space of the drum, means for admitting saturated steam into said passages, and means for withdrawing superheated steam from the tube space of the drum.

5. In a boiler, a boiler shell, fire tubes therein, a superheater drum within said shell surrounding said fire tubes, said drum including outer and inner spaced sheets confronting the boiler shell providing steam passages opening into the tube space of the drum, means for admitting saturated steam into said passages, means for

withdrawing superheated steam from the tube space of the drum, and means suspending said drum within said boiler shell.

6. In a locomotive boiler, a boiler shell, fire tubes in said shell, a superheater shell within said boiler shell surrounding a part of the length of said fire tubes, means providing steam passages between said boiler shell and superheater shell to the tube collection communicating with the lower part of said superheater shell, partition plates within said superheater shell providing steam flow in contact with said fire tubes and progressively upwardly therebetween to the upper part of said superheater shell, and means for conducting superheated steam away from said superheater shell.
